No. 18,725.

UNITED STATES PATENT OFFICE.

ÉMILE GÉRARD, OF LIMOGES, FRANCE, ASSIGNOR TO OLIVER A. GAGER,
OF BROOKLYN, NEW YORK.

DESIGN FOR THE SURFACE ORNAMENTATION OF DISHES.

SPECIFICATION forming part of Design No. 18,725, dated November 6, 1888.

Application filed November 27, 1885. Serial No. 184,132. Term of patent 7 years.

To all whom it may concern:

Be it known that I, ÉMILE GÉRARD, a citizen of the French Republic, residing in Limoges, France, have invented or produced a new and original Design for Pitchers and other Dishes, of which the following is a specification.

This design relates to a great variety of dishes—such as pitchers, chocolate-pots, tea-pots, vegetable-dishes, sugar-bowls, tureens, &c.—provided with covers and handles.

My design pertains to the surface ornamentation of the dishes. The surface ornamentations are Egyptian in their character, and will be described in detail hereinafter.

In the accompanying photographs two different embodiments of my design are illustrated. In Figures 1 to 3 is shown what is known as a "chocolate-pot" or pitcher, and in Figs. 4 and 5 is shown what is known as a "vegetable-dish" or other covered dish. Fig. 1 is a side view of the chocolate-pot. Fig. 2 is a perspective thereof looking from the front, and Fig. 3 is a perspective thereof looking from the rear. Fig. 4 is a perspective view of the vegetable-dish looking downward obliquely upon it, and Fig. 5 is a perspective view thereof looking upward beneath its bottom.

Referring to all the drawings, the dishes to which my design is applied have sides A A, ends B B, necks D, covers E, and handles G.

The chief distinguishing feature of the ornamentation of the cover is its handle or knob F, which has the resemblance of a flower, the stem g of which appears as a rib passing in a curve over the top of the cover, as shown best in Fig. 3, the calyx h of the flower lying upon the top of the cover and the corolla i curving thence upward in curved trumpet shape, with its petals expanding on all sides and turning outwardly and downwardly. The corolla is not round, but is considerably longer than its width and nearly pointed at both ends, the ends being curved downward, all as best shown in Fig. 2. The margin of the corolla is scalloped, as shown. The top of the knob is creased or indented longitudinally, producing the flaring effect of the petals shown in Figs. 2 and 3.

The handle G on a pitcher or other similar

dish is of the customary looped contour, varied, however, according to my design, as shown in Figs. 1 to 3, by the addition of a nearly-circular projecting leaf or flange, j, at the top, and a bisected pendant, k, on the outer side, at a point nearly midway of the height of the handle. The leaf or flange j is in the semblance of a flower similar to that forming the knob F, but distorted or conventionalized to adapt it to the handle. It is spread out circularly, as shown in Fig. 3, and projects toward the front, with its edges turned up, as shown in Fig. 1. Its stem forms a central rib, g', extending down the middle of the outer side of the handle. The handle is crossed on its outer side and its edges by a series of horizontal corrugations, l l, which extend from the junction of the handle with the top C of the dish to the lower end of the bisected pendant k, being interrupted, however, by the ornament j and by a double-ribbed band, m, which passes around the handle at the junction therewith of the pendant k. The handle is uncorrugated beneath this band m. At the junction of its lower end with the dish is a band, n.

Referring to Figs. 1, 2, and 3, I will now describe the surface ornamentation on the body of the dish and cover. This is shown as impressed in low relief; but it might be otherwise applied to the surface with equivalent effect.

Around the foot of the dish extend one or more horizontal bands or ribs, r r. Above these is a horizontal band, s, consisting of upright stripes or bars with pointed upper ends, each having a narrower stripe within it having a rounded upper end, with the effect shown. Over this band s is a horizontal bar, t, and above this is a horizontal band, u, consisting of a row of convex scallops, and in each scallop a conventionalized flower, showing three petals. Between the flowers are small figures x x, simulating seeds or seed-pods. These four horizontal bands r s t u form together the border design L, which extends entirely around the lower portion of the dish.

The upper portion of the dish has a somewhat similar border design, M, extending around it, and overthis, on each side, is a semicircular design, N. This design N commences on the top C and extends down upon the side A, producing the effect of a flat semicircular

drapery lying upon the top and hanging down over the side. The pattern on this design N is chiefly radial, the center of the design being close beneath the neck D. At the center 5 is a conventionalized flower, v, which extends partly up into the neck. Outside of this are parallel lines, approximately arcs of circles, with parallel rows of dots. Outside of these is a circular row of figures, y y, resembling ovals drawn to a point, or nearly so, at their smaller ends. Outside of these is a simulation of a chain, z, with pendants, the latter arranged radially; and outside of all there is a marginal line terminating the edge of the 15 pattern.

The border M, which appears to pass beneath the design N, is composed of a series of bands, as follows: A coarse chain between parallel lines constitutes a band, a', as best seen 20 in Fig. 2. Beneath this is a band, b', composed of a row of elongated oval figures arranged vertically side by side, appearing as a fringe of pendants hanging from the band a'. The bands a' b' extend entirely around the dish. 25 On the ends BB of the dish are two other bands, c' and d'. The band c' is composed of two zig-zag lines crossing each other back and forth, forming a succession of diamond-shaped figures. Straight parallel lines above and below this pattern complete the band. The band 30 d' is a fringe of pendants similar to the band b'.

The ornamentation of the cover E consists of the row of oval figures y y, depressed beneath the surrounding surface, and outside of 35 them a row of raised beads or corrugations. The depressed surface of the figures y is ribbed with transverse lines.

The surface ornamentation of the dish and cover shown in Figs. 4 and 5 is substantially 40 identical with that already described, comprising the ornamental borders or bands L and M

and the semicircular design N upon the dish and the border y on the cover.

I claim—

1. The design for dishes having the surface 45 ornamentation as shown and described.

2. In a design for a dish, the ornamentation for the surface thereof, consisting of the border design L, extending around the lower portion of the dish, substantially as shown. 50

3. In a design for a dish, the ornamentation for the surface thereof, consisting of the semi-circular, concentric, and radial pattern N, extending from the top of the dish and depending over the side thereof, substantially as 55 shown.

4. In a design for a dish, the ornamentation for the surface thereof, consisting of the border design M, extending across the upper portion of the ends of the dish, substantially as shown. 60

5. In a design for a dish, the ornamentation for the surface thereof, consisting of the semi-circular pattern N, extending from the top of the dish down upon the side thereof, and the border design M, extending around the upper 65 portion of the dish and interrupted by the pattern N, so that it appears to pass beneath the latter, substantially as shown.

6. In a design for a dish, the ornamentation for the surface of the cover thereof, which consists of the border design extended around the cover and characterized by a row of ovals drawn to a point, as shown, and depressed beneath the surrounding surface, and a row of beads or corrugations exterior thereto. 70

In witness whereof I have hereunto signed my name in the presence of two subscribing witnesses.

ÉMILE GÉRARD.
